Ford W. Harris

UNITED STATES PATENT OFFICE

FORD W. HARRIS, OF LOS ANGELES, CALIFORNIA, ASSIGNOR TO PETROLEUM RECTIFYING COMPANY OF CALIFORNIA, OF LOS ANGELES, CALIFORNIA, A CORPORATION OF CALIFORNIA

ELECTRICAL DEHYDRATOR WITH FREE MOVING LIVE ELECTRODE

Application filed August 3, 1926, Serial No. 126,834. Renewed October 13, 1931.

My invention relates to the art of dehydrating oil and water emulsions and it is particularly applicable to the dehydration of petroleum emulsions in which the water 5 appears in the form of small particles suspended in the oil. It has been found that these water particles are often so fine that they will not settle out of the oil if it is allowed to stand for a considerable length 10 of time. If, however, the emulsion is passed between electrodes charged with a suitable high electromotive force the water particles are agglomerated into larger masses which tend to settle rapidly out of the oil. It has, 15 however, been found that in many cases water particles tend to collect in the dehydrator after agglomeration in such a manner as to form conducting paths which short-circuit the electrodes and prevent further treatment.

It is an object of my invention to provide a dehydrator in which petroleum emulsions may be dehydrated and in which any concentration of water at any one point is prevented. In the typical form of electrical dehydrator, one of the terminals of the high tension transformer which supplies energy to the dehydrator is grounded to the tank which either forms the grounded electrode 20 or is connected to grounded electrodes carried inside said tank. It has been found that by placing live electrodes inside the tank and rotating same that the formation of short-circuiting water masses may be prevented and there are a considerable number 25 of patents showing live electrodes which are rotated by means of a suitable source of power placed outside the tank.

It is an object of my invention to provide 30 an electrical dehydrator having a live electrode suspended in the tank which is free to rotate, this live electrode being supported on friction reducing bearings so that it is free to turn and to also provide means for 35 rotating the masses of emulsion inside the treater in such a manner that the live electrode is carried around with the moving mass of emulsion. This movement of emulsion and the electrode tends to prevent the concentration of water masses at any particu-

lar point between the electrodes and thus prevents the electrodes from being short-circuited by such masses.

Further objects and advantages will be made evident hereinafter. 55

Referring to the drawings which are for illustrative purposes only,

Fig. 1 is a sectional elevation through a dehydrator embodying my invention.

Fig. 2 is a section on a plane represented 60 by the line 2—2 of Fig. 1.

Fig. 3 is a section through the friction reducing means.

Fig. 4 is a section through the electrical contact-making means. 65

In the form of the invention illustrated in the drawings, 10 is a tank having a flat bottom 11 and a coned top 12. The top 12 is connected to a dome 13 having a removable cover 14. Projecting outwardly from one 70 side of the dome 13 is a cylindrical extension 15 into which an insulator 16 projects. This insulator has an opening through which a conductor 17 projects. The conductor 17 is connected at its outer end to one end of the secondary of a transformer 18, the other end of this secondary being connected through a wire 19 to the tank 10. The primary of the transformer 18 is fed from any suitable source of alternating current, not shown. In practice I prefer to use a transformer which will provide a potential of from 11,000 to 22,000 volts between the wires 17 and 19. Projecting upwardly inside the shell 10 and supported on the bottom 11 is a stationary grounded cylindrical electrode 20, this electrode being formed of sheet metal and perforated at 21 and 22. Suspended in a primary chamber between the tank 10 and the electrode 20 is an outer live electrode 25 which is formed of metal wire screen and which is secured at its upper end to a cone 26. The cone 26 also carries an inner live electrode 27 which is also cylindrical in form and is formed of metal wire screen, this electrode extending in a secondary chamber defined inside the grounded electrode 20. The cone 26 is suspended from a rod 28 which is connected into a flange 29 to which a rod 30 is also connected as shown in Fig. 4. Resting 85

90

95

upon the top of the flange 29 which is preferably of brass or copper and making a good electrical contact therewith is a metal ring 31 to which the wire 17 is electrically connected. The purpose of the flange 29 and the ring 31 is to provide a freely sliding electrical connection between the wire 17 and the live electrodes 25 and 27. The rod 30 extends upwardly inside a casing 35 and is secured 18 to a flange 36 which is suspended on balls 37 from the casing 35. The purpose of the balls 37 is to provide a friction-reducing bearing on which the entire live electrode structure is supported so that it is free to revolve. The 18 casing 35 is suspended on a rod 38 which in turn is suspended on electrical insulators 39 secured to the cover 14.

The oil to be dehydrated is supplied through a pipe 40, having a valve 41, to a 20 pump 42, by means of which it is pumped through a valve 43 and a nozzle 44 into the interior of the tank 10. The nozzle 44 is placed tangentially inside the tank as shown in Fig. 2, and is so directed as to force the 25 oil into the tank tangentially, thus setting up a whirling motion in the fluid in the tank. Clean oil may be withdrawn from near the top of the tank by means of a pipe 50, and a portion of this oil may be carried downward- 30 ly through a pipe 51 and the valve 52 to the suction side of the pump 42 or it may be drained through a pipe 53 through a valve 56 to suitable storage. A vent 54 is provided in the top of the treater and a heating coil 35 55 may be provided in the bottom, if desired. Water or mud is withdrawn from the treater through a pipe 57.

The method of operation of the invention is as follows:

40 The valve 52 being closed and the valve 41 being open, the pump 42 is started and the tank is filled with emulsion to a point above the level of the pipe 50. The valve 41 may then be closed and the valve 52 may be opened 45 so that oil is circulated from the top of the tank through the pipes 50 and 51 and through the pump 42 and the nozzle 44 back into the tank 10. Due to the direction in which the nozzle 44 delivers oil to the treater a rotation 50 or whirling motion of the fluid in the treater is set up, the speed of which may be governed by the speed of the pump 42. The live electrodes 25 and 27, being formed of screen and being supported on the ball bearings 37 55 so that they will turn with very little friction, are carried by the movement of the fluid so that they rotate inside the tank 10 and about the grounded electrode 20. Current is now thrown on the transformer 18 and a potential is set up between the live electrodes 25 and 27 and the grounded electrode which 60 consists of the interior surface of the tank 10 and the grounded electrode proper 20. A dehydrating action immediately takes place 65 and a separation of the oil and water occurs,

the clean oil rising to the top of the tank and the water falling to the bottom. As soon as the upper portion of the tank is filled with clean oil, it is possible to open the valves 56 and 41 and close the valve 52, thus allowing 70 raw material to be circulated into the treater through the electrode field and out through the pipe 50. As soon as the treater is operating properly a valve 58 in the pipe 57 may be opened slightly, thus allowing water to 75 be drawn off continuously from the bottom of the treater.

I claim as my invention:

1. In an electrical dehydrator, the combination of: a tank; a live electrode situated 80 inside said tank and electrically insulated therefrom; means for injecting fluid into a mass of liquid in said tank in such a manner as to set up a movement of said liquid in said tank; and means for so supporting said 85 electrode that it moves with the movement of said mass of liquid.

2. In an electrical dehydrator, the combination of: a cylindrical tank; a cylindrical electrode situated inside said tank and electrically insulated therefrom; means for injecting fluid into a mass of liquid in said tank in such a manner as to set up a movement of said liquid in said tank; and means 90 for so supporting said electrode that it moves 95 with said liquid.

3. In an electrical dehydrator, the combination of: a cylindrical tank; a cylindrical live electrode situated inside said tank and electrically insulated therefrom; a cylindrical grounded electrode projecting inside said 100 live electrode; means for injecting fluid into a mass of liquid in said tank in such a manner as to set up a movement of said liquid in said tank; and means for so supporting said 105 live electrode that it is free to move with said liquid.

4. In an electrical dehydrator, the combination of: a cylindrical tank; a cylindrical live electrode situated inside said tank and 110 electrically insulated therefrom; a cylindrical grounded electrode projecting inside said live electrode; means for injecting fluid into a mass of liquid in said tank in such a manner as to set up a rotation of said liquid in said tank; and means for so supporting one of 115 said electrodes that it is free to move with said liquid.

5. In an electric fluid treater, the combination of: a cylindrical tank; a grounded 120 electrode disposed in said tank to divide the space therein into an annular primary chamber and a central secondary chamber; a live electrode having a central element extending into said central chamber and an outer element extending into said annular chamber; means for rotatably supporting said live electrode; means for injecting fluid into a mass of liquid in said annular chamber to 125 set up a continuous movement in said liquid, 130

the action of said moving liquid on said outer element causing said live electrode to rotate; and means for introducing a fluid to be treated into said annular chamber.

5 6. A treater as defined in claim 5 in which said live electrode elements comprise annular screens.

7. A treater as defined in claim 5 in which said live electrode elements comprise cylindrical screens, and said grounded electrode is cylindrical in shape.

10 8. A treater as defined in claim 5 in which said grounded electrode is perforated to permit fluid to pass therethrough between said 15 treating chambers.

9. A treater as defined in claim 5 in which said live electrode elements comprise annular screens, and in which said grounded electrode is perforated to permit fluid to pass 20 therethrough between said treating chambers.

10. In an electric treater, the combination of: walls defining a space in which is positioned the emulsion to be treated; a rotatably 25 mounted electrode in said space; means for rotating said electrode by moving the body of emulsion in said space; and means for establishing a difference in potential between said electrode and said walls.

30 11. A combination as defined in claim 10 in which said electrode is formed of screen.

12. In an electric treater, the combination of: a tank; a live electrode extending downward in said tank and cooperating therewith 35 in defining an annular treating space; means for introducing a fluid to be treated tangentially into said tank at a point below the lower end of said live electrode; fluid draw-off means communicating with the upper end 40 of said tank; and fluid draw-off means communicating with the lower end of said tank.

In testimony whereof, I have hereunto set my hand this 23rd day of July, 1926, at Los Angeles, California.

45 FORD W. HARRIS.
